R. E. BOORAEM.

BUILDING MATERIAL.

APPLICATION FILED JAN. 12, 1912.

1,163,613.

Patented Dec. 7, 1915.

Inventor

Robert E. Booraem
By John L. Barker
Ass. Attorney

UNITED STATES PATENT OFFICE.

ROBERT E. BOORAEM, OF FORT COLLINS, COLORADO, ASSIGNOR OF ONE-FOURTH TO
WILLIAM H. BARKER, OF NEW YORK, N. Y.

BUILDING MATERIAL.

1,163,613.

Specification of Letters Patent.

Patented Dec. 7, 1915.

Application filed January 12, 1912. Serial No. 670,882.

To all whom it may concern:

Be it known that I, ROBERT E. BOORAEM, a citizen of the United States, residing in the city of Fort Collins, and the county of 5 Larimer and State of Colorado, have invented new and useful Improvements in Building Material; and I do declare the following to be a full, clear, and exact description of my invention, such as will enable 10 others skilled in the art to which it appertains to make and use the same, reference being had to the accompanying drawings, and to the figures of reference marked thereon, which form a part of this specification. 15 My invention relates to improvements in building material of a nature which may be used for insulating purposes in the construction of buildings and other structures.

One of the principal objects of my invention resides in the construction of roofs 20 which will be impervious to heat or cold.

Another object of my invention resides in the provision of material especially adaptable for roofing and similar purposes.

25 In the drawing: Figure 1 is a cross section of a roof illustrating the application of my improved building material. Fig. 2 is a plan view of a single unit of my building material. Fig. 3 is a section taken on the line 30 3—3 Fig. 2, looking in the direction of the arrow.

The same reference characters indicate the same parts in all the views.

Let the numeral 5 designate the roof of a 35 car or other structure. To this roof metal shingles 14 are applied and arranged in rows 7, 8, and 9. The body portion of this shingle is hollow as shown at 15, and is provided with a groove 16 in one end and with a 40 tongue 17 at the opposite end. The tongue 17 is solid, whereby it is possible to form a perforation 18 therein, for the reception of the fastening device. The groove 16 is formed in a solid part of material of a thickness 45 equal to the difference between the walls of the vacuum chamber and the opposite sides of the groove has walls of increased thickness as compared with the walls of the

vacuum chamber. The opposite sides 19 and 20 of the groove 16 are thus of solid material 50 and are respectively provided with registering openings 20 and 22, which openings register with the opening 18 in the tongue 17 of the adjacent shingle when the said shingle is in position on the roof. The fastening 55 devices are then inserted through the openings when in the aforesaid registering position and enter the roof or wood work upon which the shingles are laid.

Attention is here called to the fact that 60 the apex of the roof disclosed in Fig. 1 may be capped off with a V-shaped vacuum strip 29 which straddles the apex of the roof and extends throughout the length of the latter.

While I have described and illustrated 65 herein a specific form of my invention, it is understood that the same may be varied and modified without departing from the spirit of my invention and the domain of the appended claim.

Having thus described my invention what I claim is:

A hollow building tile having a solid extension at one extremity of less thickness than the body portion and constituting a 75 tongue, this being perforated, and the tile having at its opposite end an extension of approximately the thickness of the hollow tile and grooved, whereby it is adapted to receive the tongue of an adjacent member, 80 the opposite walls of the said grooved extension being provided with perforations that register with the perforations of the tongue of an adjacent member when two tiles are properly placed together, whereby 85 fastening devices may be passed through the registering perforations securing the tiles in position on the structure to which they are applied.

In testimony whereof I affix my signature 90 in the presence of two witnesses.

ROBERT E. BOORAEM.

Witnesses:

JNO. G. POWELL,
FRANK W. SWIFT.
